UNITED STATES PATENT OFFICE.

KARL F. NELSON, OF KELLOGG, IDAHO.

RIFLE-BOX.

1,104,919.

Specification of Letters Patent. Patented July 28, 1914.

Application filed February 21, 1913. Serial No. 749,904.

To all whom it may concern:

Be it known that I, KARL F. NELSON, a citizen of the United States, residing at Kellogg, in the county of Shoshone and State 5 of Idaho, have invented certain new and useful Improvements in Rifle-Boxes, of which the following is a specification.

This invention relates to that class of ore separators known as self-discharging rifle 10 boxes, the same comprising a stationary box or trough containing riffles which gather the values and deflect the same into a launder arranged alongside the box.

It is the object of the present invention 15 to provide a novel arrangement of riffles to be hereinafter described in detail, whereby the apparatus is made to operate with a greater efficiency, and also to provide a launder for each side of the rifle-box, the 20 riffles being arranged to deflect the values into both launders.

The invention also has for its object to provide a structure which is simple and durable, the number of parts being reduced 25 to a minimum.

In order that the invention may be better understood, reference is had to the accompanying drawing in which—

Figure 1 is a plan view of a rifle box and 30 launders constructed and arranged in accordance with the invention. Fig. 2 is a side elevation partly in section on the line 2—2 of Fig. 1. Fig. 3 is an enlarged transverse section on the line 3—3 of Fig. 1.

Referring specifically to the drawing, the rifle box is of any suitable length and has a bottom 5 which is crowned transversely and is formed of sheet steel, the side edges of which are bent down to form flanges 6 35 for attachment of the sides 7 of the box, said sides being also of sheet steel. In order to simplify and cheapen the structure, and reduce the number of parts to a minimum, the sides 7 are continued downward from 40 the bottom 5 of the box as indicated at 8, and are then bent outward horizontally as indicated at 9, and then upward as indicated at 10 to form the launders. The parts 8 and 10 form the side walls of the launders 45 and the parts 9 form the bottom thereof. Thus it will be seen that the box and launders require only three pieces of sheet steel,

the sheets forming the launders being bolted or otherwise secured to the flanges 6 as indicated at 11.

In the box, on the bottom 5 thereof, are mounted angular riffles 12 which may be small strips of steel bent intermediate their ends and fastened to the bottom in any suitable manner so that they may be removed 60 at any time when necessary. As shown in Fig. 1, the apices of the riffles are at the longitudinal center of the box, from which the two ends of the riffles extend divergently to the sides 7 of the box, the inclination being in the direction of the lower or discharge end of the box. The riffles are also set closer together at the lower end of the box 65 than at the upper or receiving end thereof, and a few of the lowermost riffles are divided at the center of the box to provide a narrow space therebetween.

In the side walls 7 of the box, close to the bottom 5 thereof, and at the outer end of each ruffle 12, is a discharge opening 13.

The box, as well as the launders are deeper at their discharge ends than at their receiving ends, and the box is set so that it inclines toward its discharge end.

In operation, ore and water are discharged 80 into the box at its upper or highest end. As the ore passes over the riffles, the values are gathered by the latter and with the assistance of the water carried through the openings 13 into the launders, and as the ore 85 passes down to the lower end of the box where the riffles are set closer together, the latter continue to gather the finer particles, all of which are gathered, the rocks being forced over the riffles and out of the lower 90 end of the box. The angularity of the riffles and the crowning of the bottom 5 of the box, cause the values to spread and pass from opposite sides of the box into the launders.

By spacing the lowermost riffles at their 95 inner ends, the liability of the waste being carried sidewise with the values to the launders is reduced to a minimum. The waste is allowed to pass down the rifle box along 100 the center line thereof in the space between the inner ends of the riffles, whereas the values are carried sidewise by the riffles to the launders. The waste does not follow

the values but is discharged at the lower end of the rifle box.

I claim:

A rifle box having side outlet openings and a series of oblique riffles, the riffles at the discharge end of the box being spaced apart at the longitudinal center line of the box, from which latter they extend divergently in opposite directions to the sides of

the box, the inclination being in the direction of the discharge end of the box.

In testimony whereof I affix my signature in presence of two witnesses.

KARL F. NELSON.
